UNITED STATES PATENT OFFICE.

CHARLES SCHEFFRES, OF NEW YORK, N. Y., ASSIGNOR TO CHARLES SCHEFFRES & CO., OF NEW YORK, N. Y., A COPARTNERSHIP COMPOSED OF CHARLES SCHEFFRES AND LOUIS SCHEFFRES.

DESIGN FOR PRINTED FABRIC.

Application filed March 23, 1925. Serial No. 12,821. Term of patent 7 years.

To all whom it may concern:

Be it known that I, CHARLES SCHEFFRES, a citizen of the United States, residing at New York, in the county of New York and State of New York, have invented a new, original, and ornamental Design for Printed Fabric, of which the following is a specification, reference being had to the accompanying drawing, forming part thereof.

The figure is a plan view of the printed fabric, showing my new design.

I claim:

The ornamental design for printed fabric, as shown.

CHARLES SCHEFFRES.
